WINDING REEL

William Schroeder, Chicago, Ill., assignor to Acme Steel Company, Chicago, Ill., a corporation of Illinois

Application October 19, 1942, Serial No. 462,466

7 Claims. (Cl. 242—72)

This invention relates to improvements in winding reels and its purpose is to provide an improved device for winding strip steel and the like in spiral coils. The present invention is an improvement upon that described and claimed in the copending application of Chester M. MacChesney for Letters Patent of the United States, Serial No. 395,967, filed May 31, 1941, now Patent No. 2,299,101, Oct. 20, 1942, and upon the inventions described in the copending application of Allen B. Wilson, Serial No. 462,457, filed October 19, 1942, and in my copending application for Letters Patent of the United States, Serial No. 462,465, filed October 19, 1942.

In said application of Chester M. MacChesney, there is disclosed an improved winding reel in which the power for effecting rotation is applied directly to the segments on which the strip material is wound and in which the expansion of the annular series of segments is effected, and their contraction controlled, by a tapered expanding member mounted for movement by power means longitudinally of the axis of the reel. In that construction, the segments are anchored securely at one end to a rotatable member and the power for rotating the reel is applied directly to the segments at points adjacent the region where the coil of strip material is wound. When the segments are expanded or contracted, they tilt in a radial direction with respect to the rotatable member on which they are mounted.

In the said copending application of Allen B. Wilson there is disclosed a form of winding reel which embodies the principles of construction disclosed in the said application of Chester M. MacChesney while improving upon that construction by providing two series of core segments which are capable of being independently expanded to provide a continuous annular surface upon which the strip material is to be wound, whereas in the form of device disclosed in said application of Chester M. MacChesney the lateral edges of the segments are separated from each other in the expanded condition of the core so that the inner convolutions of the coil are bent slightly at the points where they contact with the edges of the segments and may have their surfaces marred at those points.

In my said prior application also, the core comprises an outer series of segments and an inner series of segments, but the inner segments are adapted by their outward movement to effect the expansion of the outer segments through the action of coacting wedging surfaces, and a com-

plete cylindrical surface is formed in the expanded condition of the core.

In the constructions disclosed in the first two of these copending applications, all of the segments are pivoted at their inner ends on a rotatable disk or drum and the outer segments shown in my said copending application are similarly pivoted. In the constructions of all of said applications, therefore, there is a tilting movement of some or all of the expansible segments about their inner ends when the expansion and contraction occurs which makes it impossible to maintain a complete surface contact between the wedging members which are shaped as frustums of cones and the inclined wedging surfaces of the segments with which they contact, except in the expanded condition of the core.

The principal object of the present invention is to improve upon all of the constructions disclosed in the copending applications referred to by providing a winding reel made up of a plurality of complementary segments, in combination with means applied directly to the segments for rotating them, and means for effecting the radial expansion and contraction of the segments while maintaining their outer surfaces upon which the strip material is wound parallel at all times with the axis of rotation of the core. A further object is to provide an expansible winding reel of the type referred to in which the winding surfaces are maintained parallel with the axis of rotation during expansion and contraction and in which the expansion of the segments of the core is effected by wedges movable longitudinally of the axis of the core and adapted to maintain surface contacts over substantial areas with inclined wedging surfaces formed on the segments in all stages of the expansion or contraction. A further object of the invention is to provide a winding reel comprising a plurality of complementary segments which are capable of being expanded by the longitudinal movement of a member having wedging surfaces formed thereon when that member moves in one direction and which are capable of being contracted upon movement of that member in the other direction by improved contracting means including a flexible member surrounding the segments. Still another object of the invention is to provide a winding reel made up of a plurality of complementary segments capable of radial movement for effecting the expansion and contraction of the core of the reel in combination with means movable in one direction for expanding said segments and movable in the opposite direction for permitting the contraction thereof.

and a device operated in unison with the movement of said last-named means in said last-mentioned direction for simultaneously contracting said segments. Other objects relate to various features of construction and arrangement which will appear more fully hereinafter.

The nature of the invention will be understood from the following specification taken with the accompanying drawings in which one embodiment is illustrated. In the drawings,

Figure 1 shows a longitudinal vertical section through a winding reel embodying the principles of the present invention and illustrating the segments of the core when they are expanded;

Fig. 2 shows a partial longitudinal vertical section similar to that of Fig. 1, illustrating the relative positions of the parts when the core is contracted;

Fig. 3 shows an end elevation of the winding reel illustrated in Fig. 1, looking in the direction of the arrows 3-3 shown on Fig. 1;

Fig. 4 shows a vertical section taken on the line 4-4 of Fig. 1;

Fig. 5 shows an end elevation of the core of the winding reel in the contracted condition shown in Fig. 2, the view being in the direction indicated by the arrows 5-5 in Fig. 2;

Fig. 6 shows a vertical section taken on the line 6-6 of Fig. 1;

Fig. 7 shows a sectional view taken on the line 7-7 of Fig. 1;

Fig. 8 shows a sectional view taken on the line 8-8 of Fig. 1;

Fig. 9 shows a sectional view taken on the line 9-9 of Fig. 2; and

Fig. 10 is a diagrammatic view showing the means for simultaneously actuating the wedging members by which the expansion of the segments is effected and their contraction controlled, and for actuating the means for releasing the segments to permit their expansion or positively effecting their contraction.

As illustrated in the drawings, the improved winding reel comprises a core 15 made up of a plurality of outer segments 16 and a plurality of inner segments 17 which are arranged to be expanded by a plurality of axially movable expanding members 18, 19 and 20. The outer segments 16 are provided with arcuate surfaces 16^a and the inner segments 17 are similarly provided with outer arcuate surfaces 17^a and, when the core is expanded, as shown in Figs. 1 and 3, the surfaces 16^a and 17^a, being arranged alternately, form a continuous cylinder upon which a coil of strip steel 21 or the like is adapted to be wound. The outer end portions of the segments 16 and 17, upon which the winding takes place, are generally triangular in cross section, as shown in Figs. 3, 4 and 5. The outer segments 16 are each provided with inwardly converging wedging surfaces 16^b which are adapted to coat with similarly inclined outwardly converging wedging surfaces 17^b formed upon the inner segments.

All of the segments 16 and 17 are of considerable length and extend into a housing 22 through an opening 22^a in the end wall thereof, as shown in Fig. 1. Within this opening 22^a, there is mounted a roller bearing unit 23 comprising an outer ring 23^a of channel form which embraces the opening 22^a, an inner bearing ring 23^b, a series of cylindrical bearing members 23^c mounted in complementary channels in the rings 23^a and 23^b, and a pair of annular packing rings 23^d, of felt or the like, which prevent the access of

dust to the members 23^c. The inner diameter of the inner ring 23^b is such that, when the segments 16 and 17 of the core 15 are expanded, the outer arcuate surfaces of these segments contact with the bearing ring 23^b so that a firm bearing support is provided for the core during the operation of winding.

At points located somewhat inwardly from the bearing unit 23, the segments 16 and 17 are re-

duced in cross section to form longitudinally extending arms 16^d and blades 17^d, respectively, and these arms are enlarged at their inner ends to form the heads 16^d and 17^d, shown particularly in Figs. 1, 2, 7 and 9. These enlarged heads are positioned within the hub 25^a of a driving gear 25 which has its outer portion positioned between the two radially extending flanges 22^b and 22^c of the housing. The gear 25 meshes with a driving pinion 26 secured upon a driving shaft 27 which is journaled in bearings in an extension of the housing and driven by an electric motor or other source of power. The gear 25 has its hub portion journaled in roller bearing units 28 which are secured within the flanges 22^b and 22^c of the housing and to the hub of the gear, as shown in Fig. 1, and these roller bearing units are retained in place by an annular plate 29 and by the annular flange 30^a of a housing 30 hereinafter referred to. The hub 25^a of the driving gear 25 is provided with inwardly extending lugs or keys 25^d which are tapered inwardly and which have a wedging engagement with the tapered grooves or keyways 16^e which are formed in the enlarged heads 16^d of the outer segments.

The enlarged heads 16^d of the outer segments are shaped like the forward ends of these segments which have previously been described, each head 16^d being provided with inwardly converging wedging surfaces 16^f, shown in Fig. 7, which are adapted to coat with outwardly converging wedging surfaces 17^f formed on each of the enlarged heads 17^d of the inner segments. Inasmuch as the segments are arranged alternately, with the wedging surfaces 17^f of one head 17^d coating with the wedging surfaces 16^f of two adjacent outer segments, it will be apparent that radial outward movement of the heads 16^d and 17^d will effect the radial expansion of the inner ends of the segments and cause the heads 16^d of the outer segments to expand into unitary interlocking engagement with the hub of the driving gear 25 by virtue of the wedging engagement of the keys or lugs 25^d with the tapered recesses 16^e formed in the outer segments.

As previously indicated, the radial expansion of the segments is effected by the expanding members 18, 19 and 20 which have wedging engagement with the inner segments only. The two forward expanding members 18 and 19 are mounted upon the reduced forward portion 32^a of a shaft or rod 32 and are spaced apart by a sleeve 33, the forward expanding member 18 being secured in position against the sleeve by a nut 34 which engages the threaded end of the rod. The expanding member 20 is mounted upon the rear reduced portion 32^c of the rod or shaft and is held in place against the shoulder at the end of the central portion of this shaft by a nut 35 engaging a threaded portion of the shaft as shown in Fig. 1. Each of the expanding members 18, 19 and 20 is constructed in the form of a frustum of a pyramid and the flat inclined faces of each of these expanding members are adapted to coat with inclined wedging surfaces formed upon the inner sides of the inner segments 17.

That is, the inclined wedging surfaces 18^a of the expanding member 18 are adapted to coact with the longitudinally inclined wedging surfaces 17^a which are formed upon the inner sides of the forward ends of the inner segments 17 , while the opposite inclined wedging surfaces 19^a of the expanding member 19 are adapted to coact with the longitudinally inclined wedging surfaces 17^b which are formed upon the inner segments 17 , and the opposite wedging surfaces 20^a of the expanding member 20 are adapted to coact with the longitudinally inclined wedging surfaces 17^c which are formed upon the enlarged heads 17^d of the inner ends of the inner segments 17 . The inclined wedging surfaces 17^a , 17^b and 17^c are of the same inclination with respect to the axis of the rod or shaft 32 and the inclined wedging surfaces 18^a , 19^a and 20^a are of the same inclination with respect to the axis of this shaft so that, in all relative positions of the expanding members and the inner segments, the flat wedging surfaces of the members 18 , 19 and 20 maintain their contacts with the inner flat wedging surfaces 17^a , 17^b and 17^c . By reason of the use of these flat wedging surfaces on the expanding members and on the inner projecting parts of the inner segments, it is possible to maintain substantial surface areas of contact between the expanding members and the inner segments in all stages of the expansion and contraction of the core.

The core is shown in its contracted condition in Fig. 2 of the drawings and the longitudinal movement of the rod 32 and of the expanding members toward the right, as viewed in that figure, to bring about the expansion of the core to the condition shown in Fig. 1, is effected, in the embodiment illustrated, by fluid pressure, preferably compressed air, which is applied to a cylinder 30^d forming a part of the housing 30 previously described. The reduced portion 32^c of the rod extends into this cylinder through the end wall or head 30^e thereof and this rod is rotatably mounted in a piston 37 . The reduced extremity 32^b of the rod is secured in a thrust-bearing unit 38 which is secured to the end of the rod by a washer 39 and a nut 40 . A cap 41 is secured to the piston 37 over the nut 40 and the washer 39 , forming a fluid-tight seal over these parts. Leather gaskets 37^a are secured to the opposite faces of the piston 37 and coact with the inner wall of the cylinder 30^d . The piston 37 is provided with a tubular extension or sleeve 37^b which extends through the head 30^e of the cylinder where it is engaged on its outer side by a packing gland 42 which serves to compress the packing material 43 and thus form a fluid-tight joint around the sleeve 37^b when this sleeve reciprocates in the head 30^e . An end plate or head 44 is secured to the end of the cylinder 30^d and is so shaped as to accommodate the cap 41 when the piston 37 is in its extreme right-hand position as shown in Fig. 1.

The movement of the piston 37 to the position shown in Fig. 1 is effected by admitting compressed air or the like through the pipe 45 which leads through the head 30^e of the cylinder to the space around the sleeve 37^b and this forces the rod 32 and the expanding members 18 , 19 and 20 toward the right, as viewed in Fig. 1, thereby bringing about the radial outward movement of the segments 17 and the consequent radial outward movement of the outer segments 16 , all parts of which segments move uniformly with the outer surfaces 16^a and 17^a extending at all times parallel to the axis of rotation of the core. When

it is desired to permit the contraction of the core, compressed air is admitted through the pipe 46 to the space within the head 44 , thereby causing the piston 37 and the connected parts to move toward the left to the position shown in Fig. 2. In order to prevent endwise movement of the segments during the last-mentioned movement of the piston 37 and of the expanding members 18 , 19 and 20 , the enlarged heads 16^d and 17^d of these segments are secured to a retaining plate 47 which is attached to the hub portion 25^a of the driving gear by means of the studs 48 . A series of headless bolts or studs 49 are threaded into the ends of the heads 16^d and 17^d of the segments and these studs engage radially elongated slots 48^a which are formed in the retaining plate, as shown in Figs. 1, 2 and 9. The threaded ends of these studs 49 are engaged by lock nuts 50 which overlap the slots 48^a and hold the segments of the core against endwise movement with respect to the retaining plate 47 while permitting radial movement thereof when the core is expanded and contracted. The plate 47 acts as a base plate against which the ends of all of the segments are accurately positioned so that the adjacent longitudinally inclined wedging surfaces on the several inner segments properly line up with each other for engagement by the expanding members.

The movement of the expanding members 18 , 19 and 20 toward the left as viewed in Fig. 1 merely permits the contraction of the segments of the core but does not positively effect that contraction and means are therefore provided for moving the segments positively inward when the expanding members are moved toward the left, as viewed in Figs. 1 and 2. This contraction might be effected in various ways as, for example, by the means shown in the copending applications above referred to, but it is preferred to bring about this contraction by the novel form of contracting means shown in the drawings which comprises a channel-shaped casing 52 which is mounted within the housing 22 and which is constructed in the form of a ring having its opening directed inwardly toward the core. On its upper side, the outer wall of this casing 52 is provided with openings to permit the passage of a steel cable 53 which is looped once around the segments of the core with one end attached to a socket member pivotally connected to a pair of ears 22^d formed on the casing 52 and with the other end portion extending through an opening 22^e and attached by a coupling 54 to a piston rod 55 , as shown in Fig. 6. This piston rod is mounted to reciprocate in a packing joint 56^a formed in the head 56^b of a cylinder 56 and this piston rod has secured thereon within the cylinder a piston 57 . The cylinder is closed at its other end by a head 56^c . Supply pipes 58 and 59 for compressed air or the like lead to the heads 56^b and 56^c and the compressed fluid admitted through these pipes effects the reciprocation of the piston 57 and the consequent expansion or contraction of the loop of the steel cable 53 which extends around the segments of the core within the casing 52 . When compressed air is admitted through the pipe 58 , the piston 57 moves toward the right, as viewed in Fig. 6, thereby contracting the cable around the segments and forcing them inwardly so that the portion of the core within the coil of material 21 is contracted to permit the removal of this coil. When compressed air is admitted through the pipe 59 , the piston 57 is moved in the other direction, thus pushing the cable 53

and causing it to expand and move out of contact with the outer arcuate surfaces of the segments of the core. When the segments of the core are contracted, it is necessary for the portions of the segments 17 upon which the inclined surfaces 17^b are formed to move inwardly to a point where these wedging surfaces would engage the large central portion of the rod 32 if they were not hollowed out and the end portions of these wedging surfaces have therefore been cut away as shown at 17^c.

In order that the pistons 37 and 57 may be operated in unison in the proper directions, the connections for supplying compressed air or other fluid to the cylinders 30^d and 56 are preferably connected in the manner shown in Fig. 10 and are operated by a common control valve 60 to which compressed air or the like is supplied through a pipe 61. An exhaust pipe 62 leads from this control valve and the pipes 45 and 55 are connected together and supplied with fluid from the valve through a pipe 63. The other cylinder supply pipes 46 and 58 are connected together and supplied from the valve 60 through a common supply pipe 64. With these connections, it will be apparent that upon turning the valve 60 to admit compressed air from the pipe 61 through the pipe 45 to the left-hand end of the cylinder 30^d, for the purpose of expanding the core, compressed air will at the same time be admitted to the right-hand end of the cylinder 56 thereby releasing the cable 53 from its contracting engagement with the segments. On the other hand, when compressed air is admitted through the pipe 46 to move the expanding members 18 and 19 and 20 toward the left, as viewed in Figs. 1 and 10, compressed air will at the same time be admitted through the pipe 58 to the left-hand end of the cylinder 56 and thus actuate the piston 57 to contract the cable 53 about the segments of the core.

From the foregoing description, it will be apparent that the present invention provides a winding reel of the type described in applicant's copending application in which there is obtained a substantial area of surface contact between the longitudinally movable expanding members and the wedging surfaces which are formed on the inner sides of the inner segments and that this substantial surface contact is maintained in all positions of the expanding members while, at the same time, the radial movements of the segments are effected without disturbing the parallel relationship of the outer arcuate surfaces 16^a and 17^a of the segments and the axis of the core. The present invention also provides a rigid and unitary driving connection between the driving gear and the segments of the core when these segments are expanded and there is also provided a separate bearing head for the segments which functions to support the core when the segments thereof are expanded. Although, in the embodiment illustrated, the bearing is located in proximity to the place where the coil is wound and the driving gear is positioned some distance away from the bearing support, the relative positions of these parts might be interchanged and the lengths of the arms 16^c and 17^c of the segments might be substantially shortened in order to locate the bearing support and the driving connection in close proximity to each other.

Although one form of the invention has been shown and described by way of illustration, it will be understood that it may be constructed in various other embodiments without departing from the scope of the appended claims.

I claim:

1. The combination in a winding reel, of a rotatable core comprising a plurality of radially adjustable segments upon which strip material is adapted to be wound, means movable longitudinally of said core for expanding said segments upon movement thereof in one direction and for permitting the contraction of said segments upon movement thereof in the opposite direction, and means for positively contracting said segments upon movement of said expanding means in said opposite direction, said contracting means comprising a cable extending around said segments and adapted to be drawn taut upon movement of said expanding means in said opposite direction.

2. The combination in a winding reel, of a rotatable core comprising a plurality of radially adjustable segments upon which strip material is adapted to be wound, means movable longitudinally of said core for expanding said segments upon movement thereof in one direction and for permitting the contraction of said segments upon movement thereof in the opposite direction, means for positively contracting said segments upon movement of said expanding means in said opposite direction, said contracting means comprising a cable extending around said segments and adapted to be drawn taut upon movement of said expanding means in said opposite direction, and means for drawing said cable taut and releasing it.

3. The combination in a winding reel, of a rotatable core comprising a plurality of radially adjustable segments upon which strip material is adapted to be wound, means movable longitudinally of said core for expanding said segments upon movement thereof in one direction and for permitting the contraction of said segments upon movement thereof in the opposite direction, means for positively contracting said segments upon movement of said expanding means in said opposite direction, said contracting means comprising a cable extending around said segments and adapted to be drawn taut upon movement of said expanding means in said opposite direction, and means acting in unison with the movements of said expanding means for drawing said cable taut and releasing it.

4. The combination in a winding reel, of an annular series of radially adjustable segments upon which strip material is adapted to be wound, an annular bearing and a ring gear surrounding said segments, some of said segments having longitudinally inclined wedging surfaces, some of said wedging surfaces being located within said ring gear, and means including a plurality of expanding members movable longitudinally of said core and engaging said wedging surfaces to effect the radial expansion of said segments within said annular bearing and within said ring gear.

5. The combination in a winding reel, of a plurality of radially adjustable segments upon which strip material is adapted to be wound, a ring gear surrounding the inner ends of said segments, means for effecting the radial expansion of said segments within said gear, a retaining plate attached to said gear and extending across the ends of said segments, said plate being provided with radial slots and means engaging said slots and said segments for effecting the endwise positioning of said segments while permitting radial movement thereof.

6. The combination in a winding reel, of a rotatable core comprising an annular series of outer segments and an annular series of inner segments, said segments of each series being arranged alternately with respect to those of the other series and having a plurality of pairs of similar wedging surfaces coacting with the wedging surfaces of the other series, said inner segments having inner wedging surfaces inclined longitudinally of the axis of the core, an expanding member movable longitudinally of the core and having inclined wedging surfaces coacting with said longitudinally inclined wedging surfaces on said inner segments, a driving gear having a hub surrounding said expanding member and portions of said segments, means for forming a driving connection between said hub and said outer segments while permitting relative radial movement therebetween, a retaining plate attached to said hub and extending radially inward at the ends of said segments, and means

for connecting all of said segments to said plate and permitting radial movement of said segments with respect to the axis of said core.

7. The combination in a winding reel, of an annular series of radially adjustable segments upon which strip material is adapted to be wound, a bearing ring surrounding said segments adjacent the place where said strip material is adapted to be wound, said bearing ring being adapted to engage said segments when they are expanded and to be spaced from said segments when they are contracted, a ring gear surrounding said segments at a place displaced longitudinally of said segments from said bearing ring and having a driving engagement with said segments in all radial positions of said segments, means for expanding said segments into engagement with said bearing ring and within said ring gear, means for contracting said segments, and means for rotating said ring gear.

WILLIAM SCHROEDER.
